UNITED STATES PATENT OFFICE.

FELTON VOLLMER, OF WINSTED, MINNESOTA.

PARTY-LINE TELEPHONE SYSTEM.

No. 851,458.

Specification of Letters Patent.

Patented April 23, 1907.

Application filed November 22, 1906. Serial No. 344,589.

To all whom it may concern:

Be it known that I, FELTON VOLLMER, a citizen of the United States, and a resident of Winsted, in the county of McLeod and State 5 of Minnesota, have invented a new and Improved Party-Line Telephone System, of which the following is a full, clear, and exact description.

My invention relates to party line telephone systems of the general type represented by that described in my Patent # 774,543, dated November 8, 1904 and used for selective signalling between stations.

My invention further relates to providing 15 such a system with an automatic time-controlled cut-out, whereby the system after use will return automatically to its normal condition within a predetermined length of time.

My invention further relates to certain improvements in the electrical connections, the form of various parts, and various constructional details whereby the general efficiency of the system is improved.

Reference is to be had to the accompanying drawings forming a part of this specification, in which similar characters of reference indicate corresponding parts in all the figures.

Figure 1 is a diagram of three stations, certain mechanical parts at said stations being shown in perspective, and stations numbered 2 and 4 being shown as in proper condition for conversation, station number 3, meaning 35 while, being shown as locked out; Fig. 2 is an enlarged diagram of the station numbered 3, certain parts appearing in perspective, the mechanism at this station being here shown however, as in its normal condition, the line 40 being inactive; Fig. 3 is an enlarged fragmentary section through the casing, showing certain movable parts, and indicating how the latter are actuated; Fig. 4 is an enlarged section upon the line 4—4 of Fig. 3, looking 45 in the direction of the arrow, and showing a rear view of the gears 78, 81, and parts immediately controllable thereby for the purpose of effecting certain circuits used particularly in calling.

The boards 5 and 6 (see Fig. 3) represent the rear and front casing walls of the instrument at each station, and which support the revolvable parts. The front wall 6 is provided with a circular aperture 7 into which 55 fits a collar 8 supporting a fixed plate 9 of circular form.

A shaft 10 is journaled within the plate 9 and the rear wall 5, thus being adapted to turn. Mounted rigidly upon this shaft is a cam 11 provided with a short flange 12, and 60 a longer flange 13; each of these flanges is of arcuate form and rigid upon the cam, the flange 13 extending from a bushing 14 of insulating material to one of the extreme outer edges of the cam, the flange 12 being spaced 65 a short distance from the bushing, and extending to the outer edge of the cam.

The bushing is of insulating material, thereby enabling the flanges 11, 12 to be of metal. It is not intended for any current to 70 pass through them. The flanges are each adapted to engage a pin 15 mounted upon a contact arm 16, the latter being pressed downwardly by a leaf-spring 17. A contact hook 18 is disposed adjacent to the arm 16 75 and is free to swing slightly, excess of movement being prevented by limiting-stops 19 disposed upon its opposite sides. This hook 18 is provided with contact points 20, 21, is made of metal, and is normally drawn to the 80 right, according to the view presented in Fig. 2, by means of a spring 22.

Mounted rigidly upon the shaft 10 is a disk 23, provided with notches 24, 25 spaced apart by a distance representing 90° or one-quarter of the peripheral circumference of the disk. Adapted to enter the notches 24, 25 is a tooth 26 mounted upon a lever 27 which is journaled at 28 and is adapted to swing. An armature 29 is mounted upon 90 the upper end of this lever, for actuating it.

A gear wheel 30 is rigid upon the shaft 10. Intermediate of this gear wheel 30 and the disk 23 is a gear wheel 31 and a ratchet wheel 32 practically integral with each other, being 95 connected by a sleeve 34 (see Fig. 3). This gear wheel 31 and ratchet wheel 32 are loose upon the shaft, and, of course, turn as a unit, their movements being independent of the movements of the disk 23 and the gear 30. 100 Meshing with the gear 30 is another gear wheel 35 connected rigidly with which is a pinion 36 meshing with another gear wheel 37; the pinion 38 of this wheel last mentioned, meshes with a wheel 39, the latter 105 having a winding shaft 41 which is connected by a spiral spring 40 with a post 42. The winding stem 41, being of ordinary construction, is merely shown diagrammatically.

Meshing with the gear 31 is a gear 43 having pinions 44, 44^a, the pinion 44^a meshing with a gear 46 having a pinion 45. The gear

46 meshes with a pinion 47 mounted upon an escapement wheel 48. The latter works a pallet 49, the latter and the escapement wheel together constituting an escapement 5 which causes a pendulum 50 to vibrate. Driven from the pinion 45 is a gear 51 having a pinion 52, and meshing with this pinion is a gear 53 having a pinion 54; the latter meshes with a gear 55. This gear is mounted upon 10 a winding stem 56 connected by a spiral spring 57 with a post 57^a. The winding stem 56 (being of known construction) is shown diagrammatically. The escapement wheel 48 is driven solely by the action of the 15 spring 57, but when the disk 23 is free to rotate it turns at the same speed as the shaft 10, though driven independently thereof. The gear 58 is provided with a stop-pin 59 and is connected with a spiral spring 60 20 which is comparatively weak and is also tolerably short.

An arm 61 is provided with a tongue 62, bent laterally toward the gear 58, and against which the pin 59 may stop; this tongue 62 25 therefore, serves as a limiting stop for preventing excessive movement of the gear 58 in one direction. A pin 63 serves as a journal for the arm 61. A stub shaft 64 serves to connect the spring 60 with the gear 58. 30 The upper end of the arm 61 is provided with a hook portion 65 which rests upon a spiral cam 66, the outermost or peripheral surface of the latter terminating in a point 67. This cam 66 is rigid upon the shaft and is so arranged that, relatively to the rotary motion of the shaft 10, the point 67 lags a trifle behind the outer end of the flange 12. (See Fig. 2). A brush 68 of spring metal presses upon the shaft 10 and thus serves as a contact member. The shaft 10 is provided with a 35 boss 69 which is adapted, upon the revolution of the shaft, to make engagement with a contact spring 70 so as to move the same radially outward or away from the shaft, as indicated in Fig. 4.

A contact arm 71 is pivotally mounted in the position indicated in Fig. 4 and is adapted to rest against a stop pin 72. A leaf spring 73, presses the arm 71 toward the 50 stop pin. The contact spring 70 is provided with a tooth 75 against which the outer end of the contact arm 71 may rest. A stop pin 76 prevents undue movement of the contact spring 70. Encircling the shaft 10 is a sleeve 55 77 of insulating material. A gear 78 is journaled upon this sleeve and is provided with a pin 79 and also with a hub 80, the latter extending along the sleeve 77 for the purpose of affording a good bearing for the contact 60 spring 70. The gear 81 meshes with the gear 78 and is mounted upon a stub shaft 82. Secured rigidly upon the stub shaft is a crank 83 provided with a handle 84. By grasping the handle and turning the crank, 65 the gears 81, 78, will be rotated as will be un-

derstood from Figs. 3 and 4. The gear 78 is provided with a contact spring 85. When the crank 83 is moved to its normal position, indicated by zero, (see Fig. 4), the pin 79 raises the arm 71 slightly, and enables the tooth 75 to snap under it, and to support it out of engagement with the stop pin 72, thereby making an electric circuit through the arm 71 and the spring 85.

A contact arm 85^b, mounted rigidly upon one end of the shaft 10, carries a contact spring 85^a. The plate 9 of insulating material immediately back of the arm 85^b, is provided with a number of contact pins 86, 87, 88, extending entirely through the plate as 75 will be seen from the sectional view in Fig. 3. These contact pins may be engaged from the front side by the contact spring 85^a, and also from the back by the contact spring 85. A contact pin 87^a, located just above the pin 85 80 86, is connected by a wire 87^b, with a contact pin 87^c, the latter being disposed a little distance away, and at the top of the dial.

The various stations are all equipped alike with the exception that at each station a particular wire 89, 90 is connected with a particular contact pin 87, 88; each station thus having an individuality with respect to the connection of its particular wire 89, 90, with its particular contact pin. For instance, as 95 indicated in Fig. 1, the station 2 at the left has the wire 89 connected with its contact pin 87, while at station 3 the wire 90 is connected, not with the contact pin 87, but with the contact pin 88; and at station 4, a wire 90 100 91 is connected with a contact pin 89^a.

At each station a casing or board 92 is provided for the purpose of supporting some of the parts. The magneto generator 93 is of the usual construction. A switch hook is 105 shown at 94 and is adapted to support a receiver 95. The local battery circuit 96 is equipped in the usual manner and is provided with a primary transformer winding 97, which acts inductively on a secondary 110 winding 98. Abnormal contacts 99, 100, are closed when the switch hook 94 rises into its abnormal position.

Connected with the ground 101 is a ground wire 102 which joins a wire 103. The latter 115 is connected by a wire 104 with the generator 93, the latter being in communication with the switch hook 94, and from the switch hook 94 a wire 105 leads upwardly to the contact arm 16. A wire 106 is connected 120 with wires 103, 104, and leads to the brush 68. Connecting the wire 103 and the ground wire 102 with the secondary winding 98, is a wire 107. A battery is shown at 108 and is connected by a wire 109 with the contact 125 arm 71.

A wire 110 leads from the battery 108 to a relay 111, and from this relay a wire 112 leads to the line 113. The relay 111 is provided with a movable armature 114 and a 120

contact 115, the latter being connected by a wire 116 with a wire 110. From the armature 114 a wire 117 leads to a bell magnet 118, the latter being connected by a wire 119 with a clapper contact 120 operating the clapper, which strikes the twin gongs 121. An insulating link 18^a Fig. 2 connects the hook 18 with the clapper. The contact 120 is connected by a wire 122 with the wire 109. Connected with the wire 112 is a wire 124 leading to a releasing magnet 125, the latter being connected by a wire 126 with the contact pin 87^c extending through the plate 9 as above described.

The operation of my system is described as follows: We will first suppose that the line is inactive and that each station is in its normal condition as indicated in Fig. 2: Each contact arm 16 now rests upon the upper contact point 20 of the contact hook 18 and is supported, for the time being, independently of the cam 11. In other words, each pin 15 has just dropped over the rear or upper end of the flange 13. The position of the shaft 10 is now such that the disk 23 cannot rotate, its notch 24 resting upon the tooth 26. The hook 65 of the arm 61 rests upon a comparatively thin portion of the cam 66 thus causing the gear 58 to be temporarily out of mesh with the pinion 44, the spring 60 maintaining the gear 58 in such a position that the pin 59 carried by this gear engages the under side of the limiting stop 62. The contact arm 85^b, which serves also as an indicating needle as above explained, now rests upon the contact pin 87^c. The receiver 65 rests as usual, upon the switch hook, and the battery circuit and all the other circuits are open. Everything is motionless except the train of gearing consisting of the following members: spring 57, gear 55, propelled thereby, pinion 54, gear 53, pinion 52, gear 46, pinion 47, escapement wheel 48 (driving the pendulum 50); also pinion 44 driven by gear 46 and driving gear 43 which turns gear 31, and consequently turns ratchet wheel 32, which is practically integral therewith as above explained; hence, as the disk 23 is stationary, the ratchet wheel 32 merely turns idly under the pawl 33, the spiral spring 40 thus saving its power. The conditions just described apply to every station so long as the line remains idle. Suppose now, that a subscriber, say at station 4, desires to call a subscriber at station 2; the subscriber at station 4 grasps the handle 84 and turns the crank 83 to zero, (if it is not already there) and then to the second ordinal of the series. If he had wanted station 5, he would have moved the crank 83 to the fifth ordinal. In turning the crank to the proper ordinal, the gear-wheel 78 is turned to the same extent in the opposite direction, so that the contact spring 85 carried by it engages the rear face 65 of the contact pin 87, this pin extending

through the plate 9 as elsewhere explained. During this movement of the contact spring 85, the arm 85^b does not move for the reason that the gear-wheel 78 rotates independently of the arm 85^b. The contact spring 85 now resting on the contact pin 87, the calling subscriber next actuates his generator 93. An alternating current is thus sent over the following circuit: ground 101, wire 102 of station 4, wire 103, wire 104, generator 93, wire 105, contact arm 16, tooth 20 (upon which the latter now rests; see Fig. 2), contact hook 18, wire 123, wire 112, line 113 to all stations, thence downward from the line at each station, through wire 112 and wire 124 and (being unable to enter wire 123 because the generator circuit not being in use is open as usual) through releasing magnet 125, wire 126, contact pin 87^c, wire 87^b, contact pin 87^a, contact arm 85^b (still resting on this contact pin) shaft 10, brush 68, wire 106, wire 103, wire 102, to ground 101, thence returning through ground to calling station. The circuit just traced, being duplicated at each of the stations, is a so-called "bridge circuit" based upon the use of an excess of power, so that regardless of considerable waste of current through a small number of stations, there is sufficient energy to actuate all of the magnets 125 upon the entire line. At the calling station (in this instance, station 4), the releasing magnet 125 is energized by a shunt circuit from the wire 112 as follows: wire 112, wire 124, releasing magnet 125, wire 126, contact pin 87^c, contact arm 85^b, shaft 10, brush 68, wire 106, wire 104, generator 93, wire 105, contact arm 16, contact hook 18, wire 123, wire 112, to wire 124, whence the circuit began; in other words in energizing the main line by means of wire 112 part of the current from this wire slits off and passing through the magnet 125 returns to the generator. It will thus be seen that every releasing magnet 125 upon the entire line, including the calling station, is energized; each armature 29 is thereupon attracted and the withdrawal of each tooth 26 allows the several disks 23 to begin turning under the impulse of the gears 35, 37, 39, their connections and spring 40; disk 23 turns at the same speed as the gear 31 and presses the pawl 33 into the teeth of the ratchet wheel 32. This occurs notwithstanding the fact that the ratchet wheel 32 is driven by the lower train of gearing actuated by spring 57; for the time being therefore, the pressure of the pawl 33 upon the ratchet wheel 32 causes the disk 23 and ratchet wheel 32 together with the gears 30, 31, to rotate as if locked rigidly together. The shaft 10 now turns until the tooth 26 clicks into the notch 25; that is to say, the shaft and all parts mounted thereupon turns a distance representing three-quarters of a revolution. In doing this, the contact arm 85^b passes in succession over 130

each of the contact pins 87, 88, stopping at the contact pin 87^c. At the instant when the arm 85^b passes over the contact pin 87, the contact spring 85^a, carried by this arm, makes engagement therewith; this contact spring 85^a is placed, for the moment, in electrical communication with the contact spring 85 carried by the gear-wheel 78 (see Fig. 3; position of arm 85^b indicated by dotted lines). There is thus completed, at this particular instant only, a battery circuit which cannot affect any station excepting station 2, this battery circuit being as follows: ground 101 at station 4, wire 102, wire 103, wire 106, brush 68, shaft 10, contact arm 85^b, contact spring 85^a, contact pin 87, contact spring 85, gear wheel 78, hub 80, contact spring 70, contact pawl 71 (for the moment in engagement with contact spring 70), wire 109, battery 108, wire 110, relay 111, wire 112, to line 113; from line 113 the current cannot get to the ground except at station 2, for the reason that this is the only station in which the contact pin 87 is provided with a wire. The current flows to the ground at station 2 as follows: wire 112, relay 111, wire 110, wire 89, contact pin 87, contact spring 85^a, contact arm 85^b, shaft 10, brush 68, wire 106, wire 103, wire 102, to ground 30 where the circuit started. The relays 111 at stations 2 and 4 being thus energized, the following local circuit is completed at each of these stations: battery 108, wire 110, wire 116, armature 114, (now attracted by magnet 111), wire 117, bell magnet 118, wire 119, contact 120, wire 122, back to battery 108. This rings the bells at stations 4 and 2, the duration of the ring being quite short. The shafts 10 continuing their revolutions so as to complete the three-quarter turn, the other several stations are left in the condition indicated in Fig. 1. That is to say, at stations 2 and 4 the contact arms 16 rest now upon the lower contact points 21, while at all of the other stations, for instance, station 3, the arms 16 are raised out of engagement with the contact points 20. The parties now take down their respective receivers and may talk over the following circuit: ground 101, wire 102, secondary winding 98, receiver 95, switch hook 94, wire 105, contact arm 16, contact hook 18, wire 123, wire 112, to line; thence at station 2, through wire 112, wire 123, hook 18, contact arm 16, wire 105, switch hook 94, receiver 95, secondary winding 98, and wire 102, back to ground 101. The circuit just traced is the main or secondary circuit of the line and is energized inductively by the local circuit 96 of either station in the manner well known. The conversation being finished, either party actuates his generator 93; this completes the following circuit: ground 101 at station 4, wire 102, wire 103, wire 104, generator 93, wire 105, contact lever 16, contact point 21, contact hook 18, wire 123, wire 112, to line, thence to all of the other stations; wire 112, wire 124, releasing magnet 125, wire 126, contact pin 87^c, contact spring 85^a, contact arm 85^b, shaft 10, wire 106, wire 103, wire 102, to ground 101. The circuit just traced energizes the release magnet 125 at all stations including the one thus ringing off, say station No. 4. A shunt from the circuit at wire 112, station 4, energizes the release magnet 125 at that station. This shunt circuit is as follows: wire 112, wire 124, releasing magnet 125, wire 126, contact pin 87^c, contact spring 85^a, contact arm 85^b, shaft 10, brush 68, wire 106, wire 104, generator 93, wire 105, back to wire 112, whence the shunt circuit started. The several bridge wires being thus energized, the several armatures 29 are attracted and the several disks 23 are set in motion. The disks then make a quarter turn, each disk turning its proper shaft 10 to that extent. Hence, at each station the arm 85^b is brought to rest upon the contact pin 87^a, the contact arm 16 is brought to a position where it rests upon the tooth 20, and generally speaking, every part is in the position indicated in Fig. 2. The hook 65 now occupies its lowermost position (see cam 66, Fig. 2), the arm 61 is down, the gear 58 is out of mesh with the pinion 44, and the spring 60 has brought this gear 58 into such position that the pin 59 rests against the stop 62. Suppose however, that the subscribers do not finish their conversation within a reasonable, predetermined time, say for instance, five minutes, or neglect to ring off. In this event the gear wheel 58 being in mesh with the pinion 44 for the time being, and being constantly turned thereby reaches such a position that the pin 59 presses the lever 27 to the left, thereby disengaging the tooth 26 from the notch 25. This releases the disk 23 and allows the shaft 10 to turn until stopped by the entrance of the tooth 26 into the notch 24; in other words, the shaft and all parts mounted upon it, turn one-fourth of a revolution. This restores the shaft to its normal condition shown in Fig. 2, and having the status described above at the beginning of the operation.

It will be understood that the parts shown in Fig. 4 are so arranged that if they happen to be in normal position as indicated in Fig. 2, and the handle 83 is turned as above described, preparatory to calling, if the handle be left in any position except at zero the arm 71 is not left in contact with the contact spring 70. When the handle is turned to zero, the arm 71 is lifted by the pin 79 and rested upon the shoulder 75, but the circuit through the releasing magnets 125 is still open and must remain so, as long as the shaft 10 is at rest. It follows therefore, that the releasing circuit cannot be closed except as

above described, no matter in what position a subscriber may leave the handle 83. When the shaft 10 is set in motion, the boss 69 on shaft 10 lifts the contact spring 70 and drops the contact arm 71, thus still leaving the releasing circuit open. This circuit can never be closed, therefore, except in the orderly manner above set forth in detail. It will be noted therefore, that my system embodies the feature of a cut-out, a selective function, an alarm controllable by a relay, batteries having open circuits, and various factors adapted to promote safety, convenience and economy. It will also be noted that the gear wheel 58 is controllable by clock-work and allows the calling and called stations to remain in condition for talking, without interruption or being overheard by other stations, for a limited period, only, preferably five minutes; nevertheless conversation may continue for a longer period if the line should not be wanted by others on the line, as either subscriber may call a second or a third time.

The system admits of special use in connection with measured service.

Having thus described my invention I claim as new and desire to secure by Letters Patent:

1. In a party-line telephone system, the combination of a revolute shaft, contact mechanism to be opened and closed thereby, a talking circuit to be completed and broken

by movements of said contact mechanism, a train of clock-work, mechanism controllable by said train of clock-work for releasing said revolute shaft, and means for turning said revolute shaft. 35

2. In a party-line telephone system, the combination of a talking circuit, contact mechanism for controlling the same, clock-work for actuating said contact mechanism, a time wheel for meshing with said clock work, means for throwing said time wheel into and out of mesh with said clock-work, and mechanism for restoring said time wheel 45 to its normal condition when out of mesh with said clock-work.

3. In a party-line telephone system, the combination of a talking circuit, contact mechanism for controlling the same, a revolute shaft for actuating said contact mechanism, means for holding said revolute shaft in a predetermined position for the purpose of allowing conversation to proceed over said talking circuit, and time controlled mechanism for releasing said revolute shaft. 50 55

In testimony whereof I have signed my name to this specification in the presence of two subscribing witnesses.

FELTON VOLLMER.
